(57) **CLAIM**

The ornamental design for a cosmetic container, as shown and described.

DESCRIPTION

FIG. 1 is a perspective view of the cosmetic container, showing our new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The broken lines shown are for the purpose of illustrating parts of the article forming no part of the claimed design. The “prmr” logo shown in the reproductions, and forming part of the claim, is a registered trademark of Amorepacific Corporation.

1 Claim, 6 Drawing Sheets
